UNITED STATES PATENT OFFICE.

CURTIS HUSSEY VEEDER, OF HARTFORD, CONNECTICUT, ASSIGNOR TO THE VEEDEER MANUFACTURING COMPANY, OF HARTFORD, CONNECTICUT, A CORPORATION OF CONNECTICUT.

TACHOMETER.

1,379,947.

Specification of Letters Patent. Patented May 31, 1921.

Application filed May 28, 1919. Serial No. 300,408.

To all whom it may concern:

Be it known that I, CURTIS HUSSEY VEEDEER, a citizen of the United States, residing in the city of Hartford, in the State 5 of Connecticut, have invented certain new and useful Improvements in Tachometers, of which the following is a specification, reference being had to the accompanying drawings, forming a part hereof.

10 This invention relates to instruments of the same general character as that shown and described in Letters Patent of the United States, Nos. 732,975 and 733,358, both dated July 7, 1903, and No. 1,016,906, 15 dated Feb. 6, 1912, in which the speed of rotation of shafts and other rotating bodies is indicated and measured by the height of a column of liquid acted upon by an impeller which is driven from or by a shaft or 20 other rotating body. The invention is concerned particularly with various features of construction and has for its object to facilitate manufacture and to improve the operation, with special reference to the attainment of a high degree of accuracy. The invention will be more fully explained hereinafter with reference to the accompanying drawings, in which is illustrated an embodiment of the invention, and in 25 30 which—

Figure 1 is a view in front elevation of a tachometer which embodies the invention, partly broken out to save space.

Fig. 2 is a top view.

35 Fig. 3 is a view in section on the plane indicated by the broken line 3—3 of Fig. 1, looking in the direction of the arrows.

Fig. 4 is a detail view in section on the irregular plane indicated by the broken 40 line 4—4 of Fig. 1, looking in the direction of the arrows.

Fig. 5 is a view in section on the plane indicated by the broken line 5—5 of Fig. 1, looking in the direction of the arrows, the 45 scale of Fig. 5, as well as of Figs. 2, 3 and 4 being larger than that of Fig. 1.

Fig. 6 is a view in section of the lower 50 part of the instrument, on the plane indicated by the broken line 6—6 of Fig. 5, looking in the direction of the arrows, the scale of this figure being somewhat larger than that of Fig. 5.

Fig. 7 is a view in section and on the same 55 scale as Fig. 6, on the plane indicated by the broken line 7—7 of Fig. 5.

Figs. 8, 9 and 10 are detail views illustrating the application of driving gears of different ratios.

Fig. 11 is a top view of the impeller casting, with its central hub and the impeller 60 shaft in section and the top plate of the casting broken away to show the impeller.

The base *a* is formed in one integral piece and is chambered as at *a'* to form part of a reservoir for the liquid. It receives from its under side a block *b* in which is formed a chamber *b'* for the reception of the impeller *c*, the chamber *b'* being closed from the bottom by a cap *b²* which is soldered to the block, the block and cap being held in place 65 by a plate *a²* secured to the base by screws *a³*. The plate *a²* and cap *b²* are formed separately for convenience in manufacture but constitute in effect a chambered cap-plate. It will be observed that there is one ma- 70 chined joint at *a⁴* and one tapered and ground joint at *a⁵* between the block *b* which forms the impeller case and the base *a*, and one ground joint *b³* between the bottom plate *b²* and the impeller case *b*. This 75 construction permits the desired accuracy of fit and tightness to be secured with less difficulty in manufacture than was possible in the former constructions.

Formed partly in the base *a* and partly 80 in the impeller case *b*, at the tapered joint *a⁵*, is an annular channel *b⁴* which communicates with the impeller chamber *b'* through radial openings *b⁵*, shown most clearly in Fig. 11. The bottom plate *a²* is recessed to 85 form a chamber *a⁶* which communicates with the impeller chamber *b'* through a central opening *b⁶* and with the reservoir *a'* by an opening *b⁷* formed through the impeller case, as shown most clearly in Fig. 6. A duct 90 *b⁸* also establishes communication between the reservoir and the upper side of the impeller chamber *b'*, so that the impeller chamber is in communication with the reservoir both from above and from below, whereby a 95 freer and more uniform circulation of the liquid is permitted. The block *b* which forms the impeller case is extended upward within the base *a*, with a cylindrical joint at 100 *a⁴* as above indicated. It has formed there- 105 in, at *b⁹*, a cylindrical bearing or guide for the driving spindle of the impeller, with vertical grooves formed therein, as at *b¹⁰*, which communicate with the bore of the block extension *b¹¹*, thus providing a way of 110

escape for the entrained air which is separated from the liquid in the impeller chamber by centrifugal action. It has been found hitherto that such entrained air or gas has occasioned considerable trouble and has required experimenting and investigation to determine the nature and cause of such trouble. Such air has a free escape from the upper end of the casing extension.

- 10 The impeller c is made with a small hub c' , from which extend the radial arms or blades c^2 , with interposed radial blades c^3 which do not reach the hub, a space thus being left at the center of the impeller as well as at 15 the outer edge; while the blades or arms are connected and supported by a thin annulus c^4 . This construction of the impeller facilitates the escape of the entrained air to the vertical grooves b^{10} as above referred to.
- 20 The impeller is driven by a shaft d , to the lower end of which it may be secured by solder or other suitable means. The shaft d is a short shaft, supported by a ball bearing d' , which is above the level of the liquid in the 25 reservoir and in which the shaft is made vertically adjustable so that the impeller, supported by the shaft, can be adjusted with accuracy to its proper position in the center of the impeller case. To this end the upper 30 end of the shaft is split and receives a screw d^2 , the head of which is tapered, so that the end of the shaft can be expanded within the sleeve d^3 of the ball bearing. The shaft and impeller are adjusted when the screw is 35 loosened and are then secured in position by driving the screw home.

The shaft d is driven by another shaft section e which similarly is supported by a ball bearing e' at its upper end, in which the 40 shaft is adjustably secured by means of the tapered screw e^2 and sleeve e^3 . The ball bearing e' is supported by a top plate or cap e^4 of a casing f , swiveled upon the base a so that it can be turned about a vertical axis 45 to more than 180° . The case f is secured upon the base by a two-part doubly flanged ring f' which engages tapered flanges f^2 on the base and case respectively, so that when the two parts of the flanged ring are set up 50 by the screws f^3 , shown in Fig. 5, the case f will be held in adjusted position. The purpose of such adjustment is to facilitate connection to the shaft or other part, the speed of rotation of which is to be indicated. The 55 driving member g is mounted in suitable bearings in an extension f^4 of the case f and the intermeshing gears, by which the shaft e is driven from the shaft g are removably secured on the respective shafts so that gears 60 of different ratios may be used according to the requirements of each particular case.

As shown in Fig. 6, the pinion g' having a split sleeve g^2 is secured on the shaft g by a nut g^3 and meshes with a bell gear i' having 65 a split sleeve i^2 secured on the shaft e by a

nut i^3 . Other gear ratios are indicated in Figs. 8, 9 and 10, the same reference characters being employed to indicate like parts although of different sizes.

In the reservoir a' is mounted the usual 70 plunger h for the purpose of regulating the height of the liquid in the reservoir by displacement. The plunger h is screw-threaded to engage a sleeve h' mounted on the extension of the impeller case b and formed at 75 its upper end with a beveled gear h^2 for engagement with a beveled pinion h^3 on the end of a shaft h^4 rotatable in a sleeve h^5 fitted tightly in the base a , the shaft h^4 being provided with a thumb-wheel h^6 outside of 80 the base whereby adjustment of the plunger can be effected readily.

The chambers a' , a^9 are connected at a^8 and a^{11} below and above the plunger h and communicate through the hollow standards 85 a^{10} with the cap a^{12} . The indicator tube k having a suitable scale k' in proper relation therewith, communicates at its upper end with the channeled cap a^{12} and at its lower end with the annular channel b^4 90 through a channel b^2 controlled by a suitable valve b^3 . The formation of the supplemental chambers a^9 independent of the chamber a' in which is located the plunger, the connection of the two chambers above and 95 below the plunger and the connection of the supplemental chamber to the channeled cap permits free movement of the liquid.

The mode of operation of the improved instrument is substantially the same as the 100 mode of operation of the instruments described in the patents referred to and no further explanation is required. It will be obvious that the improvements herein described contribute to facility and accuracy 105 in construction and to uniformity and accuracy in operation.

I claim as my invention:

1. In an instrument of the character described, the combination of an integral base, 110 chambered from its under side, a block chambered from its under side to receive an impeller, and provided with a discharge opening, a reservoir chamber being formed in the base above the block, an impeller, and a chambered cap-plate to close the impeller chamber from below, a channel being formed in the block to effect communication from the chamber above the block to the upper side of the impeller chamber at its center, 115 and channels being also provided to establish communication between the chamber of the cap-plate and the chamber above the block and the under side of the impeller chamber at its center.

2. In an instrument of the character described, the combination of an integral base, chambered from its under side to form a reservoir, a block chambered to receive an impeller and having a taper fit within the 120

- base and having also a tubular extension upward through the reservoir fitted at its upper end in the top of the base, an impeller, an imperforate holding plate secured to the under side of the base to retain the block in position, and driving means for the impeller located wholly above the impeller and extended downward through the tubular extension. 5
- 10 3. In an instrument of the character described, the combination of an integral base, chambered from its under side to form a reservoir, a block chambered to receive an impeller and fitted within the base and provided with a discharge opening, a cap to close the under side of the impeller chamber, an imperforate holding plate secured to the under side of the base to retain the block and cap in position, an impeller and driving means for the impeller located wholly above the impeller, a chamber being formed between the plate and the cap, the block having an opening to establish communication between the reservoir and the last named chamber, and an opening to establish communication between the reservoir and the impeller chamber, and the cap having an opening to establish communication between the chamber under the cap and the impeller chamber, whereby the impeller chamber communicates both from its upper side and from its under side with the reservoir. 25
- 30 4. In an instrument of the character described, the combination of a base chambered from its under side to form a reservoir, a block chambered to receive an impeller and fitted within the base and having an upward tubular extension through the reservoir, the reservoir and the impeller chamber being in communication, an impeller, and a shaft extended downward through the extension of the block to support the impeller, the extension of the block being formed with air-ways to permit the escape of air from the impeller chamber. 45
5. In an instrument of the character described, the combination of a base, a block fitted in the base and chambered to receive an impeller and having also an upward extension, a ball bearing located in the upper part of the extension and having an internal sleeve, and a shaft adjustably supported in the sleeve of the bearing and having the impeller secured thereto at its lower end. 50
6. In an instrument of the character described, the combination of a base, a block fitted in the base and chambered to receive an impeller and having also an upward extension, a ball bearing located in the upper part of the extension and having an internal sleeve, and a shaft having the impeller se- 60
- cured thereto at its lower end and split and threaded to receive a tapered screw in its upper end and to be expanded thereby 65 within the sleeve of the bearing. 7. In an instrument of the character described, the combination of a base having a reservoir formed therein, an impeller casing fitted within the reservoir and having a cylindrical extension upward through the reservoir, a sleeve mounted rotatably on the extension, screw threaded externally and formed with gear teeth at its upper end, a plunger mounted adjustably on the screw-threaded sleeve, and a shaft mounted in the base and having a pinion to engage the gear teeth with the sleeve. 75
8. In an instrument of the character described, the combination of a base having an imperforate bottom, a casing mounted on the base and adjustable about a vertical axis, an impeller, a vertical driving shaft mounted in the base and casing, a horizontal driving shaft mounted in the casing above the impeller and movable therewith about the vertical axis, and intermeshing bevel gears mounted on the vertical shaft and horizontal shaft respectively. 80
9. In an instrument of the character described, the combination of a base having an imperforate bottom, a casing mounted on the base and adjustable about a vertical axis, the base of the casing having tapered, parallel flanges, a split, flanged collar embracing 90 the tapered flanges of the base and casing, means to tighten the collar in position, an impeller, a vertical driving shaft mounted in the base and the casing, a horizontal shaft mounted in the casing above the impeller, and intermeshing bevel gears mounted on the vertical shaft and the horizontal shaft respectively. 100
10. In an instrument of the character described, the combination of an integral base, chambered to form a reservoir, a block chambered to receive an impeller and having a taper fit within the base, a cap to close the impeller chamber and having a tight joint with said block, and a holding plate secured to the base and forming with said cap a chamber, an outlet chamber being formed in the tapered surfaces of the base and the block and communicating with the impeller chamber through radial openings 110 115 through the block and the impeller chamber being in communication centrally directly with the reservoir on the one side and indirectly on the other side with the reservoir through the chamber formed by the cap and the plate. 120

This specification signed this 22 day of May, A. D. 1919.
CURTIS HUSSEY VEEDER.
